GEORGE W. CODRINGTON, OF LAKewood, OHIO

FUEL INJECTION MEANS FOR INTERNAL COMBUSTION ENGINES

Application filed September 15, 1930. Serial No. 481,869.

This invention relates to liquid fuel injection means for internal combustion engines, and more particularly the invention has to do with that type of injection system wherein the fuel is supplied to the several engine cylinders from a common source which is maintained at the injection pressure.

The objects of the invention are to simplify the injection apparatus and particularly that portion thereof which confines the fuel. Briefly the invention includes cooperative valve and valve body parts wherein the fuel at the injection pressure is supplied to the valve; by way of a flexible connection, is conveyed through the valve to the injection nozzle; and the valve in closed position is maintained seated against the nozzle by the pressure of the fuel itself.

The exact nature of this invention together with further objects and advantages thereof will be apparent from the following description taken in connection with the accompanying drawings, in which Fig. 1 is an assembly view of the principal pertinent parts which comprise a fuel injection unit for a single engine cylinder, the parts being broken away to show details of construction; Fig. 2 is a detail in section of the nozzle portion of parts appearing in Fig. 1.

With reference now to the drawings the valve body is of composite construction for reasons which will appear. The principal part of the body is a plug 1 adapted for insertion in the cylinder wall of the engine to extend between the combustion chamber and the outside of the engine beyond the water jacket, as will be understood by one familiar with the art. The plug 1 has a through opening 2 externally threaded at its inner end as at 3, to receive a cap 4, which cap serves as a retainer for a nozzle 5. Above the nozzle in the bore 2 is fitted a cylindrical block 6. Thereabove is the block 7 and thereabove the block 8. A cap nut 9 is threaded into the end of the plug 1 as indicated to maintain the described assembly of these parts which together comprise the valve body.

The three blocks 6, 7 and 8 and the nut 9 have central through openings as indicated to receive the valve 10. The openings in the

two blocks 6 and 8, and in the nut 9, are preferably of the same diameter as indicated; but the opening 11 in the block 7 is of greater diameter than those in the adjacent blocks 6 and 8.

The valve diameters in the corresponding portions of the valve are of corresponding diameters so that the valve is a tight fit but slidable longitudinally in the valve body assembly. To seat or unseat its head portion 12 against the nozzle 5, the nozzle is provided with the usual valve receiving seat, and drilled discharge leads 13.

The valve has a central bore 14 which forms a fuel passage the entire length of the valve with the exception of terminating short of the valve head 12. Communicating with the nozzle end of the lead 14 the valve has a transverse drill 15 connecting with the chamber 16 in the nozzle 5.

The enlarged portion 17 of the valve fitting in the opening 11 is somewhat shorter than the block 7, so that a second annular chamber 18 is provided at the end of the block 7 removed from the nozzle, and a third annular chamber 19 is similarly formed adjacent the nozzle end. A drill 20 connects the hollow 14 of the valve with the outer chamber 18. The inner chamber 19 has communication with a pipe 21 leading to overflow, by way of a drill 22 in the block 7, a groove 23 running along the blocks 7 and 8, and a transverse drill 24 through the plug 1. The drill 24 also preferably communicates with a hollow 25 in the block 8. The outer end of the valve 10 has connection with a source of liquid fuel supply at high pressure, by a flexible tube 26, through a suitable connection including the nuts 27.

It will be apparent that fuel and pressure supplied through the pipe 26 will find its way into the nozzle chamber 16, and the chamber 18. The parts are so proportioned and arranged that in transverse sectional area the chamber 18 is greater than the nozzle opening 13, so that the valve is hydraulically unbalanced, and the fuel pressure will tend to maintain the valve seated upon the nozzle. Any slight leakage will be carried off by way of the pipe 21.

To unseat the valve to accomplish injection, a nut 28 is rigidly secured upon the outwardly extending stem portion of the valve for cooperation with a lever 29. This lever 5 29 may be fulcrumed as at 30 on supports 31 which may be integral with the plug 1, and the opposite end of the lever may be actuated through the usual push rod 32 of the usual valve gear. As will be understood by 10 one familiar with the art, the lever 29 may thus be moved counterclockwise, Fig. 1, periodically with the engine cycle and in properly timed relation therein, to lift the valve from its seat against the fluid pressure tending 15 to maintain the valve seated. Obviously, instantly the valve is thus unseated injection will take place through the nozzle opening 13, at the pressure provided from the pipe 26. Return movement of the lever 20 29 allows the pressure in the chamber 18 to instantly reseat the valve and thus cut off injection.

What I claim is:

1. Liquid fuel injection means for an internal combustion engine comprising a valve body having a valve-receiving opening and a nozzle portion, and an injection valve movable in said opening to control discharge through said nozzle, said parts being arranged 25 for cooperation to provide a pair of chambers, one communicating with the nozzle opening, the other separated from said nozzle chamber by an enlarged portion of said valve, said valve having a fuel feed passage 30 communicating with both said chambers, a flexible fuel feed connection providing fuel feed to said valve passage, the parts being so proportioned and arranged that fuel pressure forces will act in said second 35 chamber to maintain the valve seated, and means for unseating the valve periodically 40 with the engine cycle.

2. Liquid fuel injection means for an internal combustion engine comprising a valve body having a valve-receiving opening and a nozzle portion, and an injection valve movable in said opening to control discharge through said nozzle, said opening and valve having cooperative enlarged portions arranged 45 to provide an annular chamber removed from said nozzle portion, said valve having a through opening leading to said nozzle and a passage connecting said opening with said annular chamber, the parts being so proportioned and arranged that fuel 50 pressure forces at said nozzle will be communicated to said chamber and there act to maintain the valve seated.

In testimony whereof I hereby affix my 55 signature.

GEORGE W. CODRINGTON.
